Primary Examiner — Cynthia Underwood*(74) Attorney, Agent, or Firm* — The Roy Gross Law Firm, LLC; Roy Gross(57) **CLAIM**

The ornamental design for an adjustable rugged tablet frame, as shown and described.

DESCRIPTION

FIG. 1 is a front isometric view of an adjustable rugged tablet frame in accordance with the new design;

FIG. 2 is a front view thereof;

FIG. 3 is a right side elevation view thereof;

FIG. 4 is a rear view thereof;

FIG. 5 is a left side elevation view thereof;

FIG. 6 is a bottom elevation view thereof;

FIG. 7 is a top elevation view thereof; and,

FIG. 8 is a front exploded isometric view thereof.

The broken lines represent environment and form no part of the claimed design.
